UNITED STATES PATENT OFFICE.

MARTIN K. PASCO, OF NEW BRITAIN, CONNECTICUT, ASSIGNOR TO AMERICAN HOSIERY COMPANY, OF NEW BRITAIN, CONNECTICUT, A CORPORATION.

COAT-SWEATER.

1,160,195.

Specification of Letters Patent.

Patented Nov. 16, 1915.

Application filed February 21, 1912. Serial No. 679,030.

To all whom it may concern:

Be it known that I, MARTIN K. PASCO, a citizen of the United States, residing at New Britain, in the county of Hartford and State of Connecticut, have invented certain new and useful Improvements in Coat-Sweaters, of which the following is a specification.

My invention relates to improvements in coat sweaters and the main object of my improvements is to produce a coat sweater of a neat and attractive style, especially with reference to the appearance of the roll of the collar when rolled or folded at various points. That is to say, the line of fold may extend through the combined collar and border, and not cross a seam at any point.

In the accompanying drawing:—Figure 1 is a perspective view of so much of my coat sweater as may be seen when it is worn under an outer coat, and with the combined collar and border of my coat sweater. Fig. 2 is a side view of the same. Fig. 3 is a side view of the same with the collar buttoned still higher and rolled at a still higher point. Fig. 4 is a like view of the same partly broken away with the collar buttoned up still higher and rolled at a still higher point. Fig. 5 is a broken view of the combined collar and border before it is sewed upon the body of the coat. Fig. 6 is a broken view of the same before the collar portion is seamed and before the button holes are made and the buttons sewed on.

The body A of the coat is of an ordinary form of low necked coat sweater made of a knit fabric. Instead of the usual border for the front and neck portion made of a uniform width from end to end with the ulster collar seamed to its neck portion, I make the ulster collar or high collar 7 and front borders 8 and 8^a of a single piece and preferably of a seamless knit tube while the collar portion is knit flat and widened from the said border portions toward the middle to the desired width. If the combined collar and border is tubular and then flattened as shown in Fig. 5 it will be of two thicknesses from end to end. In addition to such flattening the collar is shown in Fig. 5 as folded transversely at the middle of its length, the border 8 for the right hand side of the coat being in front while the border 8^a for the left hand side is at the rear and is shown in part by break-

ing out a portion of the right hand border. The left hand border 8^a is provided with button holes 8^b and the right hand border 8 with buttons 8^c for the body of the coat, while two other buttons 8^d are sewed upon the collar at points above the larger body buttons. I also provide the edge of the collar with button loops 8^e for use in connection with the buttons 8^d on the collar.

I prefer to make the button holes and sew on the buttons while the combined collar and border is detached from the body of the coat. The combined collar and border is seamed to the coat body by its straight edge as shown in Fig. 1, the seam being indicated by the character 9. This combined collar and border may be knit in any ordinary manner. I prefer to knit the collar portion 7 flat and the border portions in a seamless tube as shown in Fig. 6. The collar portion is then formed into a tube by bringing the opposite edges together and seaming them. This is done when the knit fabric is wrong side out and then the entire tube is turned right side out. The seam 7^a is shown in Fig. 5 near the edge of the collar. This seam is on the inner surface of the collar and will show when the collar is turned down.

When a border is used that extends from the bottom upwardly, on one side then around the neck and downwardly on the other side of the front, and of uniform width throughout, the seam where the collar is seamed thereto comes at or near the point where the collar is folded outwardly or rolled over at the lowest line of roll. Such seam will make the collar roll differently than it would if there were no such seam near the line of roll. A seam in the collar and border, either longitudinal or transverse that comes near to line of roll will affect the appearance of the roll to a greater or less extent.

By my improvement the finished combined collar and border is formed of a single piece of a uniform material, finish and thickness throughout, whereby the collar rolls over so smoothly and evenly at all points as to present a neat and attractive appearance in all of the various positions.

Figs. 1 and 2 show the combined collar and border rolled over at its lowermost line of fold, the coat being buttoned by the body buttons only.

Fig. 3 shows the collar rolled over on its median line of fold the lower part of the collar then being buttoned by the lower-most collar button and loop. When the top 5 one of the collar buttons and loop are buttoned the collar may be rolled over on its uppermost line of fold as shown in Fig. 4 and if desired may be rolled up from this line and stand up without any roll or fold.

10 I claim as my invention:—

1. A coat sweater comprising a unit which constitutes a combined high collar and front border in one piece of tubular knit fabric, the said unit having one straight 15 edge while the opposite edge is provided with offsets at the upper ends of the front border portions, and a knit fabric coat sweater body, the said combined collar and border unit being secured to the edge of the 20 said coat sweater body by the said straight edge, and the said unit being of uniform thickness, material, and finish throughout and free from cross seams.

2. In a coat sweater a combined collar 25 and border composed of a single piece of knit fabric only, the same being in the form of a flattened tube having one straight

edge, the border portion being seamless tubes and the collar portion having a longitudinal seam near that edge which is opposite the said straight edge, the complete border and collar having two thicknesses only, both thicknesses being of uniform material and finish throughout their entire 30 length.

3. A coat sweater comprising in combination a knit fabric coat sweater body, and a collar and border member, the said collar and border member comprising in one piece of continuous tubular formation from end 40 to end, two front border portions interconnected by a collar portion, the said collar portion being generally of appreciably greater width than the border portions and merging at the ends by a tapered formation 45 into the said border portions and the said collar and border member being flattened and secured by one edge to the free edge portion of the said coat sweater body.

MARTIN K. PASCO.
